CLAIM

The ornamental design for a “sole for shoe,” as shown and described in the drawings.

DESCRIPTION

FIG. 1 is a front, top, and right side perspective view of a sole for shoe in accordance with the new design;

FIG. 2 is a left side perspective view thereof;

FIG. 3 is a right side perspective view thereof;

FIG. 4 is a front and top perspective view thereof;

FIG. 5 is a rear and bottom perspective view thereof;

FIG. 6 is a top plan view thereof; and,

FIG. 7 is a bottom plan view thereof.

The number “37” in a circle shown in the sole in FIG. 7 is a size indication. The number “37” in a circle shown in the sole in FIG. 7 is not part of the claimed design.

The Trademarks “ecco” in an oval, and “ecco LIGHT” shown in the sole in FIG. 7 are trademarks of the assignee, Ecco Sko A/S. The trademarks shown in the sole in FIG. 7 are not part of the claimed design.
